(57) **CLAIM**

The ornamental design for a multi-layered protective article, as shown and described.

DESCRIPTION

FIG. 1 is a top plan view of a multi-layered protective article showing our design;

FIG. 2 is a bottom plan view of the present invention;

FIG. 3 is a side elevation view of the present invention;

FIG. 4 is a side elevation view of the present invention;

FIG. 5 is a front elevation view of the present invention; and,

FIG. 6 is a rear elevation view of the present invention.

The broken lines in FIG. 1 are illustrating indicia on the tabs and form no part of the claimed design.
